LOOSE-LEAF VISIBLE INDEX BINDER

John Sehade, Holyoke, Mass., assignor to National Blank Book Company, Holyoke, Mass., a corporation of Massachusetts

Application May 5, 1937, Serial No. 140,793

4 Claims. (Cl. 129—9)

This invention relates to an improved loose-leaf binder, particularly of the type used to hold loose-leaf sheets of the visible index bookkeeping kind. In such binders the user frequently wants to shift some of the visible index sheets longitudinally of the back and there are known devices built into the binder to do this work. According to the present invention the binder is of improved construction for this purpose, particularly in regard to the mechanism to do the work of shifting the index sheets with convenience.

The character of the improvements can be understood best from a specific disclosure of the form which will be described with reference to the accompanying drawings, in which—

Fig. 1 is a plan view of the open binder, with the covers partly cut away to save space, with the cam plate for manipulating the binder back plates, shown in its outermost position;

Fig. 2 is a plan view similar to Fig. 1 of the open binder shown in the position where the prong-carrying plates may swing upwardly;

Fig. 3 is a view similar to Fig. 2, showing the prongs in the reading and writing position of the book with reference to the position of the cam plate;

Fig. 4 is a similar view with the parts in closed binder position;

Fig. 5 is a view like Fig. 1 but with the prong-carrying side plates removed to better show the underlying parts;

Fig. 6 is a view on line 6—6 of Fig. 2, but with a part removed to better show a slideable plate construction;

Fig. 7 is a view on line 7—7 of Fig. 2;

Fig. 8 is a section on line 8—8 of Fig. 1;

Fig. 9 is a section on line 9—9 of Fig. 1; and

Fig. 10 is a section on line 10—10 of Fig. 2.

The back portion of the binder is made of angle plates 1 and 2, see Figs. 8 to 10, connected for a limited transverse sliding movement. Plate 1 has turned-over end edge portions 1' to overlie and guide the end edges of plate 2 as in a groove.

The upstanding flange 3 on plate 1 has its outer edge made with a series of spaced ears 3' rounded to receive a hinge pintle. The cover 4 has a hinge plate 5 with spaced ears 5' to receive the same hinge pintle, so the cover 4 is hinged to the back plate 1. Between ears 3' there are ears 20' on the upper edge of a hinge plate 21', to which prongs 21 are attached. This plate 21' is thus hinged to the same pintle as cover 4, see Fig. 1. It will be seen from Fig. 10 that when the covers 4

and 6 are opened flat and prong carrying plates 21' are turned upwardly toward the dotted line positions, the upper ends of plates 21' will finally strike against the hinge plates 5 and 7 (against portions 5' and 7' seen in Fig. 1), and the latter 5 act as stops against any turning of the prong carrying plates beyond the vertical position of the prongs.

As will be seen in Fig. 9, plate 20 has a bottom ledge to hold plate 21' vertical in the horizontal position of prongs 21. Between plate 20 and flange 3 a latch plate 30 is mounted. It has slots 31 (see Fig. 7) in which ride headed pins attached to plate 3 to limit its movement. At each end of the back portion a bent-over finger piece 30' is provided for sliding it. When the latch is moved to the dotted position of Fig. 2, a horizontal hook piece 32 is in line with a slot opening 32' in plates 20 and 21'. This slot is shown in Fig. 7. The prong-carrying plates 20 20 and 21', in the position of the latch mentioned, can be swung upwardly as in the dotted line position of Fig. 10. The plates carry a horizontal plate 33 which is normally adapted to overlie a companion plate 34 on a similar prong-carrying arrangement pivoted on the right-hand side of the binder. This arrangement is made so that when latch plate 30 is moved to the full line position of Fig. 2, its hook 32, by engaging the plates 20 and 21' as in Fig. 2, will 30 lock plates 20 and 21', in down position for prongs 21 to stay parallel with the back plates. And with plate 33 bearing on top of plate 34, the prongs on the opposite edge of the back will be similarly held down, as will appear. The one 35 latch operable at one side of the back will serve to latch and unlatch the prong-carrying means at both sides.

The prongs 21 on the right-hand side of the book are carried by an angle plate 40, see Fig. 8, 40 and this plate is fastened to a plate 19. The upper edge of the latter is provided with spaced ears 22 hooked over pintle pin 9 and adapted to slide back and forth on said pin. This sliding movement is for the purpose of offsetting 45 the prongs 21 on one side of the book with relation to those on the other side of the book.

Cover 6 has hinge plate 7 with spaced ears 7' around pintle 9. The upstanding flange 2', of back plate 2, has spaced hooks 10 along its upper edge extending over pintle 9 and then down slightly below and on the outer edge of a slideable plate 11. This plate is adapted to slide with hooks 10 as an upper guide and the space between the edge of a cam plate 16, see 55

- Fig. 10, and flange 2' of back plate 2, as a lower guide. The upper edge of plate 11 is provided with notches to receive the ears 22 so that as plate 11 is slid back and forth on pintle 9 the prong-carrying plate 40 and its supporting plate 19, from which ears 22 extend, will also slide back and forth. The arrangement will be clear from the right-hand side of Figs. 2 and 6, particularly if it is understood that the ears 22 of Fig. 2 are engageable by the end walls of notches 17 at the top of plate 11, not appearing in that figure but shown in Figs. 5 and 6, and that whenever plate 11 is moved on pintle 9, ears 22 are all moved with the plate.
- The movable plate 11 has enough gear rack teeth 12 cut in its lower edge, as indicated in Fig. 5, to mesh with gear segment 13. The latter is pivoted on pin 14 extending up from back plate 2 through slot 15 of cam plate 16.
- Cam plate 16 is mounted on plate 2 to slide thereon with one edge in a groove 8 made by bending over the longitudinal edge 23 of plate 2. The other edge of plate 16 is close to slideable plate 11. Rollers 25 mounted on cam plate 16 engage the edge 24 to make the cam action easier. Spaced cam slots 26 are provided in plate 16 and these slots contain headed pins 27 fastened rigidly to plate 1, the heads of 27 overlying the margins of the slots. Whenever the cam plate 16 is pulled way out and pushed way in, as by end handle 28, it will be seen that slots 26, by engaging pins 27, force plate 2 to move transversely to widen the binder back and then to narrow it, respectively,—the pins 27 sliding in slots 27' cut in plate 2.
- In addition, at each full "out" and "in" movement of the cam plate 16, the stationary pin 29 on the cam plate engages the socket 30 of the gear segment 13 and rocks this gear to slide plate 11 by reason of its meshing rack teeth, first one way and then the other, so the prongs on the right-hand side of the binder are shifted first one way and then the other longitudinally of the binder and thus offset with respect to the prongs on the other side. The parts are arranged so that this prong shifting movement takes place during only part of the movement of cam plate 16, and during that part the binder back is spread apart to its limit and back plates 1 and 2 are relatively stationary. The idea is to have plates 1 and 2 move apart and close together transversely while prong-shifting plate 11 does not move longitudinally, and to move plate 11 longitudinally while plates 1 and 2 are already spread out to the limit and do not move transversely. This is the preferred operation.
- This preferred action is brought about by portions *a* of the cam slots in plate 16 which are located to hold plates 1 and 2 in spread position while pin 29 is doing its work to slide plate 11 in one direction or the other. Also portions *b* of the cam slots are located so that they will be moving plates 1 and 2 transversely in one direction or the other while pin 29 is riding in engagement with straight edges *c* on the gear segment 13 so as to hold the latter and thus plate 11 and the prongs against any longitudinal movement of the book back.
- When latch rod 38, with a finger piece 38' at each end, is shifted, the hook latch 32 may engage or disengage the margin of its slot. When disengaged, the hinge prong-carrying plate at the left may be swung upwardly to put on or take off punched sheets on that side. Plates 33 and 34 overlap and are dimensioned so that

neither set of prongs can be turned upwardly unless pin 27 is in stretch *a* of the cam slots; otherwise these plates 33 and 34 interfere with one another or with the prongs to prevent upturning movement. For illustration consider the position of the parts in Fig. 1; if the left-hand set of prongs is pulled upwardly plate 33 is in position to strike under the prongs of the right-hand set, which stops the upward movement of plate 33. But when pin 27 is in portion *a* of the cam, as in Fig. 2, it will be seen that plate 33 can swing from its lower position (see Fig. 10) and clear the ends of the right-hand set of prongs. Thus, the arrangement holds all the parts except when the latch is disengaged and the binder back is spread to the hand manipulating position for the prongs, which is the position of pin 27 in portion *a* of the cam slots.

Now that the mechanism has been described, the whole operation is as follows: With the book in tightly closed position, the back is laid on a table, the covers opened flat, the cam plate 16 pulled out until pins 27 are located at stations 50 in the cam slots. This gives the reference or writing position of the book. The prong sets are spread apart enough to loosen the pack of bookkeeping sheets at the back, but the prongs are relatively overlapped enough to hold all sheets in position against all displacement except easy turning from one side to another. Now, suppose that it is desired either to insert new sheets, take out old ones, or shift visible index sheets already in the binder up or down relatively to other index sheets already in the binder; then the cam plate is pulled out so pins 27 are positioned at stations 51 in the cam slots. The latter are cut so that the arrival of pins at their stations is perceptible to the feeling of the operator manipulating the cam plate handle, as by a little bump when the pins 27 arrive. With the pins at stations 51, both sets of prongs can be raised to vertical position, when the latch for one set is disengaged, but not otherwise. In vertical position the sheets on each set are easy to take off and put on. But the more important function of the mechanism is to give an automatic shifting of visible index sheets already in the binder on the prongs and without ever taking them off the prongs.

Fig. 4 illustrates the binder parts in closed position as when the book is ready to be closed and put away. Fig. 3 illustrates the normal reference and writing position. The number of sheets that will fill the book if in Fig. 4 position will be easy to turn over from side to side in Fig. 3 position because the prongs have been moved apart enough for such easy turning. Remembering that offset overlapping visible index sheets are carried on the prongs, it will be clear that the sheets on the right-hand side will be moved upwardly of the book when cam plate 16 is pulled out to the position of Fig. 1. The upwardly offsetting movement takes place as the prongs are in the position of Fig. 2. It is not necessary to spread them apart enough to move entirely out of overlapping position, but it is desirable to have their tips spread apart enough to clear the paper sheets on opposite sides of the book and the position of Fig. 2 will do this even when the binder is carrying sheets enough to pack tightly and fill the book when in Fig. 4 position. After the prongs move between the limits represented by stretch *a* of cam slot 26, it is desirable to move them together into greater overlapping position at each limit and the cam stretches *b* provide for

5 this. Thus, in the positions of either Fig. 1 or Fig. 3 the punched visible index sheets may be conveniently transferred from side to side of the binder without leaving the prongs, but merely riding over from one set of prongs to the other set on opposite sides of the book. It will be readily understood by those using visible index sheet binders, that any particular sheet or set 10 of sheets may be stepped up or down in their arrangement in the book by manipulating cam plate 16 and by properly turning the sheets from side to side. For example, assume that the top sheet on the right of Fig. 3 position is to be moved up one hole with respect to other sheets 15 on that side. The cam plate 16 is pulled out as in Fig. 1, the sheet turned over on the left-hand cover and held on the left-hand set of prongs. Then cam plate 16 is pushed back to position of Fig. 3 and the sheet returned to the right-hand side. When it returns, it will be higher in the set because it was lifted higher and held higher 20 on the left-hand side of the book while the right-hand set of prongs returned the other sheets to their original position. The lifted sheet, when 25 transferred to the right side, will have a lower set of holes engage the right-hand prongs than was the case before the manipulation. There are visible index binders in the prior art by which the same end result can be accomplished, so I 30 have not illustrated in detail the movement of the sheet from one position to another. My present invention relates to the improved mechanism or means for getting the sheet lifted or lowered in a convenient manner.

35 Having disclosed my improved loose-leaf binding means, I claim:

1. A visible index binder including a sectional back portion, sets of oppositely disposed prongs, one set mounted at each side of the back portion, such sets being relatively movable in two 40 directions, one direction exactly longitudinally of the binder back and one exactly transversely of the binder, a flat cam plate mounted to slide on one of the back portion sections, and mechanism operable by movement of the cam plate to move the prongs relatively transversely in a spreading direction, then longitudinally in an offset direction, and again transversely in overlapping direction when the prongs are in their 45 changed longitudinal relation.

50 2. In a loose-leaf binder the combination of a U-shaped metallic frame forming the back portion, said frame being divided so as to permit sliding movement of the upstanding sides to and from each other to decrease and increase the thickness of the binder back, prong-carrying plates mounted on said sides, so as to be movable one with respect to the other longitudinally of the back portion, two sets of prongs, one car-

ried by each plate, said sets being in opposed relation across the back portion, and mechanism combined with the parts of the back portion, including a slideable cam plate, a segmental gear and rack teeth, said mechanism being operable by sliding of the cam plate to slide the divided frame to a normal binder closed position, to a normal reading and writing position, and from the latter position through a cycle of relative prong-shifting movements in which the prongs are spread further apart in the direction of their length, shifted relatively longitudinally of the back between predetermined limits, and then at said limit shifted to replace them in the direction of their length but at a new offset relation 15 longitudinally of the back, successive sliding movements of the cam in opposite directions exactly repeating said cycle except the direction of the prong-offsetting movement which alternates at each alternation of the direction of the cam 20 plate sliding movement.

3. In a loose-leaf binder a U-shaped frame having upstanding legs and relatively slideable sides forming the back portion, a prong-carrying plate mounted to slide between predetermined 25 limits against one of the legs of the frame, rack teeth provided at the bottom edge of said plate, a gear on the frame mounted to engage the rack teeth, and mechanism operable from the end of the frame to turn said gear in opposite directions to slide said plate in opposite directions, said mechanism having connections to prevent sliding the sides of said frame relatively except when said plate is at one or the other of its 30 predetermined sliding limits.

4. In a loose-leaf binder a U-shaped frame having upstanding legs and relatively slideable sides forming the back portion, a prong-carrying plate mounted to slide between predetermined 40 limits against one of the legs of the frame, rack teeth provided at the bottom edge of said plate, a gear on the frame mounted to engage the rack teeth, and mechanism operable from the end of the frame to turn said gear in opposite directions to slide said plate in opposite directions, said mechanism having connections to prevent sliding the sides of said frame 45 relatively except when said plate is at one or the other of its predetermined sliding limits, in combination with connections between the sides of the back portion and the mechanism for sliding the prong-carrying plate whereby the binder back portion may be automatically widened and narrowed between predetermined limits upon continued operation of the mechanism after the 50 sliding movement of the prong-carrying plate 55 has stopped at either of its limits.

JOHN SCHADE.
